REBOUND CHECK FOR STARTER DRIVES

Application filed July 30, 1931. Serial No. 553,943.

This invention relates to a rebound check for starter drives and more particularly to a device in an automatic drive for preventing the starter pinion from bounding back against the engine gear when it is thrown out of mesh but which does not interfere with the initial automatic traversal into mesh.

It is an object of the present invention to provide a novel rebound check for starter pinions which is reliable and efficient and which may be readily adapted to existing types of starter gearing.

It is another object of the invention to provide such a device which is adapted to positively arrest the pinion when it is thrown out of mesh and hold it in idle position as long as the motor is spinning.

It is a further object of the invention to provide such a device which is normally in inoperative position whereby it offers no obstruction to the initial meshing movement of the pinion, but is moved into operative position by the spinning of the motor shaft.

Further objects and advantages will be apparent to those skilled in this art from the following description taken in connection with the accompanying drawing in which:

Fig. 1 is a side elevation partly in section of a starter drive embodying a preferred form of my invention showing the parts in idle position;

Fig. 2 is a detail showing the parts in locking position;

Fig. 3 is a section taken substantially on the line 3—3 of Fig. 1;

Fig. 4 is a view similar to Fig. 2 showing a second embodiment of the invention;

Fig. 5 is a detail in plan view of the locking device illustrated in Fig. 4; and

Fig. 6 is a sectional detail taken substantially on the line 6—6 of Fig. 4.

Referring first to Fig. 1 of the drawing there is illustrated a starting motor 1 with an extended armature shaft 2 having an outboard support 3 adjacent a member 4 such as the flywheel gear of an engine to be started.

An automatic drive for connecting and disconnecting the motor shaft 2 to the engine member 4 is provided comprising a power member in the form of a screw shaft 5 freely

mounted on the motor shaft and drivingly connected thereto by means of a spring 6 connected at one end to a driving head 7 fixed to the motor shaft as by means of a stud 8, and connected at the other end as by means of a stud 9 to a driven head 11 on said screw shaft.

A driving member in the form of a pinion 12 is threaded on the screw shaft in position to be moved by relative rotation therebetween into and out of mesh with the engine member 4. The pinion is normally retained in its idle position against the heel 25 of the threads on shaft 5 as shown in Fig. 1 by yielding means such as an anti-drift spring 13. As shown this spring is mounted on a smooth portion of the shaft 5 and cooperates with a stop nut 14 at one end and a stepped ring 15 at the other end which ring serves as a bearing for the front end of the pinion and also serves as a housing for the spring 13 and a spacer for the pinion 12 when the pinion is in driving position.

According to the present invention, the teeth of the pinion 12 are extended rearwardly to form an annular series of projections 16 spaced outwardly from the shaft 5. A latch 17 is pivoted as indicated at 18 in a longitudinal groove 19 (Fig. 2) in the shaft 5 with its nose 21 normally held in the space between the projections 16 and the shaft by yielding means such as a spring 22.

The latch is provided with a weighted portion 23 of sufficient mass to overcome the force of the spring 22 and cause the latch to swing outwardly when the shaft is spinning rapidly to bring the nose 21 of the latch into the path of the projections 16 as illustrated in Fig. 2, thus locking the pinion in its idle position as long as the shaft continues to spin. The locking position of latch 17 is preferably defined by a heel 20 thereon engaging the bottom of the groove 19. The trailing edge of the latch 17 is bevelled off as indicated at 24 (Fig. 3) so as to allow the projections 16 to pass over the latch in a forward direction when the pinion is thrown out to its idle position.

In the operation of the device, and starting with the parts in the positions shown in

Fig. 1, actuation of the motor causes rotation of the armature shaft 2 in the direction of the arrow *a*, which rotation is transmitted by the spring 6 to the screw shaft 5. Since the 5 latch 17 is initially held in its inoperative position by the spring 22, the rotation of the shaft 5 will traverse the pinion 12 into mesh with the engine member 4, until the spacing ring 15 abuts against the stop nut 14. Rotation is then transmitted to the engine member 10 4 for cranking purposes.

When the engine becomes self-operative, the driving load is released from the motor which accordingly spins rapidly, causing the 15 latch 17 to move outwardly into its locking position as defined by the heel 20 of said latch.

The rapid rotation of the engine member 4 causes the pinion 12 to overrun the shaft 5, 20 whereby the pinion is threaded back on said shaft to its idle position. When the pinion is thrown back to its idle position, the projections 16 thereon pass over the bevelled nose 21 of the latch 17, but when the pinion 25 strikes the heels 25 of the threads on shaft 5, rebounding of the pinion back toward meshing position with the engine member is positively prevented by the latch 17 which holds the pinion in its idle position until 30 the operator causes the motor to be deenergized.

In Fig. 4, another embodiment of the invention is illustrated showing a somewhat different form of locking means. In this embodiment a centrifugal latch 26 is pivoted as indicated at 27, in a bracket 28 which may be fixed to the driven head 11 of screw shaft 5 in any suitable way as by brazing or welding. The latch 26 is formed with an inwardly extending nose 29 bevelled as shown at 31 (Fig. 5) and adapted to engage between the projections 16 of pinion 12 when moved outwardly by centrifugal force against the action of spring 32. The operative position of 45 latch 26 is defined by engagement of the heel 33 against the surface of the bracket 28.

The operation of this form of the invention is the same as the embodiment first described except that the latch 26 when in 50 normal position rests with its nose 29 against the side of the driven head 11 of shaft 5 instead of in the space between the shaft and the projections 16.

Although certain forms of this invention 55 have been shown and described in detail it will be understood that various other forms are possible and changes may be made in the proportions and arrangements of the parts without departing from the spirit of the invention as defined in the claims appended hereto.

What is claimed is:—

1. In an engine starter, a power member, a driving member mounted thereon for rotary movement thereof and therewith and 60

for longitudinal movement into and out of engagement with a member of an engine to be started, and means on said power member adapted to be moved by centrifugal force into position to engage and lock said driving member against rotary movement with respect to said power member. 70

2. In an engine starter, a power member, a driving member mounted thereon for rotary movement thereof and therewith and for longitudinal movement into and out of engagement with a member of an engine to be started, said driving member having a projection formed thereon, and a latch mounted on said power member and arranged to be 75 moved by centrifugal force into position to engage said projection and lock the driving member against rotary movement on said power member.

3. In an engine starter, a power member, a driving member mounted thereon for rotary movement thereof and therewith and for longitudinal movement into and out of engagement with a member of an engine to be started, said driving member having an axial projection formed on one end thereof, and a latch movably mounted on said power member, normally out of the path of movement of the driving member but adapted to be moved by centrifugal force into position 95 to engage said projection and lock the driving member in its idle position. 85

4. An engine starter drive including a power shaft, a pinion mounted for rotation thereon and therewith, and connected to be moved thereby into and out of engagement with a member of an engine to be started, said pinion having axially extending teeth, and a latch pivoted on said shaft and arranged to be moved by centrifugal force into 100 position to engage said teeth and lock the pinion in its idle position. 105

5. An engine starter drive including a power shaft, a pinion mounted for rotation thereon and therewith, and connected to be moved thereby into and out of engagement with a member of an engine to be started, the teeth of said pinion being extended rearwardly to form axial projections, and a latch pivoted on said shaft to swing radially in an 115 axial plane and arranged to be moved by centrifugal force into position to engage said projections when the pinion is in its idle position. 110

6. An engine starter drive including a power shaft, a pinion mounted for rotation thereon and therewith, and connected to be moved thereby into and out of engagement with a member of an engine to be started, the teeth of said pinion being extended rearwardly to form axial projections, and a latch pivoted on said shaft to swing radially in an axial plane and arranged to be moved by centrifugal force into position to engage said projections when the pinion is in its idle 120 125 130

position, said latch being formed to allow rotation of the pinion to its idle position on the shaft, but when moved into operative position by centrifugal force, locking said pinion in idle position, and yielding means for normally maintaining said latch in inoperative position.

5 In testimony whereof I have signed this specification.

YOUSTON SEKELLA.
